UNITED STATES PATENT OFFICE

LOUIS A. GEBHARD, OF WASHINGTON, DISTRICT OF COLUMBIA, ASSIGNOR, BY MESNE ASSIGNMENTS, TO FEDERAL TELEGRAPH COMPANY, A CORPORATION OF CALIFORNIA

ELECTRON-TUBE CIRCUIT

Application filed March 26, 1927. Serial No. 178,791.

My invention relates broadly to high frequency signal transmission circuits and more particularly to a system for controlling the filament circuits of the electron tubes of the transmission circuits.

One of the objects of my invention is to provide a system for supplying the filament heating current to the filament electrodes of the tubes of a high frequency transmitter in such manner that the effective life of the filament electrodes may be prolonged.

Another object of my invention is to provide a protective system for the filament electrodes of a plurality of high power tubes in a transmission system by which sudden excess current is prevented from injuriously affecting the electron emitting properties of the filament electrodes.

Still another object of my invention is to provide a time delay circuit for energizing the filament electrodes of a plurality of electron tubes whereby the filament temperature is automatically increased from a predetermined normal value to an electron emitting temperature for running condition for preserving the life of the electron tubes.

My invention will be more fully understood from the specification hereinafter following by reference to the accompanying drawings wherein Fig. 1 diagrammatically illustrates invention in association with a high frequency electron tube transmission system where the cathode circuits are energized from direct current; and Fig. 2 shows my invention applied to an electron tube transmitter where the tubes have their filaments supplied from an alternating current source.

My invention provides for the protection of the cathode circuits of high power tubes wherein it is undesirable to have a very high starting current in comparison to running current and where it is desirable to reduce the running current to a moderate value rather than cut it off entirely during momentary interruptions in use. This is the case in the vacuum tube filament circuit, particularly in high power tubes. The filaments generally have a comparatively low resistance at normal atmospheric temperatures,

the resistance increasing to an effective high value at operating temperature. When the voltage is applied to the tube filament terminals the current will rise to a high value unless there is a current limiting device interposed in circuit therewith in accordance with the principles of my invention.

It is desirable as a matter of economy to reduce the temperature of the vacuum tube filaments to a moderate value without disconnecting the voltage entirely when the set is not actually sending out signals. This must be done automatically at a definite time after the operator releases the sending key. When the operator desires to use the set again the temperature should rise to operating value with the first click of the key, as is accomplished in the circuit arrangement of my invention.

My invention is illustrated as applied to an electron tube transmitter having oscillator tube 11 and power amplifier tubes 13 and 14 coupled through tuned circuits 25, 26 and 27 for impressing high frequency signaling energy on antenna counterpoise system 28 and 29. The cathodes 11^a, 13^a and 14^a are connected through transformer systems when the supply is alternating current as shown in Fig. 2 and when the supply is direct current the cathodes are parallel connected to the supply circuits as shown in Fig. 1.

In Fig. 2 reference character 13 designates one of the vacuum tubes, the filament 13^a of which is connected to secondary terminals 10 and 12 of a transformer 9, the center tap 11 being grounded. The primary winding of transformer 9 is connected through a rheostat 8 and a resistance 6 to an alternating current supply line 7. 5 is a time limit relay so arranged that when voltage is applied to its coil terminals 17, its contacts 18 close instantaneously and short circuit the resistance 6. When the applied voltage is disconnected holding the contacts closed for a definite time limit after which they open and remove the short circuit from resistance 6. The length of time delay is adjusted to suit the particular conditions by proper setting of the parts of the relay, the normal time being about 100

twenty seconds. Resistance 6 is of proper value to reduce the temperature of the filaments to the desired point. Rheostat 8 is of sufficient resistance to adjust the voltage at terminals 10 and 12 to proper value when resistance 6 is shunted by contacts 18.

The voltage supplying coil 17 is obtained from source 1 through contacts 19 of relay 2. Across these contacts is connected a spark 10 reducing circuit consisting of resistance 3 and condenser 4 which is not absolutely essential to the operation of the device but affords more rapid keying and lowers the liability of contacts sticking.

15 Contact 22 of relay 14 connects to the grid or other circuit 16 of the vacuum tube 13 and controls its output. The coil 34 of relay 14 and the coil 20 of relay 2 are connected in series or parallel and to line 15. This line includes the operator's key 23 and a power source 24 to operate the relays.

In normal operation, before the set is started, the operator's key 23 is open. Since there is no voltage on relay 2 the contacts 25 19 are open and therefore there is no voltage across coil 17 of relay 5, and therefore its contacts 18 are open. Resistance 6 is in the circuit and limits the current in the tube 13 when supply source 7 is closed. When the 30 operator first presses the key 23 both relays 34 and 2 are energized and contacts 22 and 19 close. Contact 19 closes circuit to 17 which in turn instantaneously closes contacts 18 shunting out resistance 6 and allowing 35 the current and therefore the temperature of filament of tube 13, to rise to operating value. Contacts 22 control the output of tube 13 and a signal is sent out. If the operator now lifts his key 23 for spacing or other reason, contacts 18 are held closed and the 40 filament temperature of tube 13 is kept at normal operating value by the time limit device of relay 5 which may be a bellows, oil dash pot or other device of similar nature. 45 If the operator's key 23 remains open for a longer period than the time limit is set for, the contacts 18 open and the filament temperature falls to the point determined by resistance 6. When the operator again closes 50 his key the operation as above described repeats.

The time delay feature as employed in the transmission circuit is a very valuable one. The life of a tube depends upon the temperature of the filament. In fact at normal operating temperature the life is lengthened considerably with a very slight drop in temperature. The high currents in starting due to the low resistance of the filament tend to injure the tube if not to cause its entire destruction. The device described corrects as far as possible these difficulties.

It should be noted that the source of tube lighting 7 may be direct current instead of 65 alternating current (Fig. 1) in which case

transformer 9 may be eliminated. If eliminated alternating or direct current may be used. It should also be noted that 13 may be some other device than a vacuum tube.

In the direct current system illustrated in Fig. 1 the cathodes 11^a, 13^a and 14^a are parallel connected and may be independently controlled through the adjustable resistors 8 and to the direct current supply line indicated at 30 in Fig. 1. The time delay apparatus heretofore described in connection with the alternating supply current system is similarly employed in the direct current supply system, so that when the operator's key 23 remains open for periods longer than the predetermined time limit the contacts open and the filament temperature falls to a value determined by the resistance 6, the filaments being always ready to be brought up to operating temperature upon the closing 85 of the operator's sending key.

The invention described herein has been found to be extremely practical in its operation on long distance electron tube transmission circuits where transmission has been effected for distances of 5,000 miles.

While I have described preferred embodiments of the invention, I desire that it be understood that modifications may be made and that no limitations upon my invention are intended other than are imposed by the scope of the appended claims.

What I claim as new and desire to secure by Letters Patent of the United States is as follows:

1. An electron tube transmission system comprising an electron tube having a cathode, a grid and a plate, a modulation circuit, a keying circuit for controlling said modulation circuit, a cathode supply source, a cathode supply circuit connected to said source and connections between said keying circuit and said cathode supply circuit whereby the supply of cathode heating energy may be modified at a predetermined time interval 100 after the opening of said keying circuit.

2. An electron tube transmission system comprising a plurality of electron tubes, a cathode supply source, a cathode supply circuit for said electron tubes connected to said source, a keying circuit for controlling the operation of said electron tubes, a relay circuit, contacts disposed in said cathode supply circuit, and controlled by said relay circuit, connections between said relay circuit and said keying circuit whereby said keying circuit directly and automatically controls the supply of energy to said cathode supply circuit from said cathode supply source at a predetermined time interval after the opening of said keying circuit by controlling said relay circuit and opening and closing said contacts.

3. An electron tube transmitter comprising a plurality of electron tube circuits, a 130

keying circuit connected with said electron tubes, a cathode supply source, a cathode supply circuit extending between said source and the cathodes of said electron tubes, and connections between said keying circuit and said cathode supply circuit for reducing the energy impressed upon said cathode supply circuit at a predetermined time interval after the opening of said keying circuit whereby said keying circuit operates to control the condition of said cathode supply circuit.

4. An electron tube transmitter comprising a plurality of electron tubes, a cathode supply circuit for said electron tubes, connections for supplying power to the cathodes from said cathode supply circuit, a keying circuit, and means controlled by said keying circuit for reducing the effective value of cathode heating energy at a predetermined time interval after the cessation of operation of said keying circuit.

5. An electron tube transmission system comprising a plurality of electron tubes, a cathode for each of said tubes, a cathode heating circuit for said electron tubes, a power supply source connected with said heating circuit, a circuit controller interposed between said power supply source and said cathode heating circuit and operative to maintain the cathodes of said tubes at an electron-emitting temperature or in a condition below an electron-emitting temperature, a keying circuit, and means interposed in said keying circuit for determining the operation of said circuit controller in said cathode heating circuit in accordance with the operation of said keying circuit and changing said cathodes from an electron-emitting condition to a condition below an electron-emitting temperature.

6. An electron tube transmission system including a plurality of electron tubes, a cathode for each of said tubes, a cathode heating circuit for said electron tubes, a power source connected to said heating circuit, a circuit controller comprising a make and break contactor in shunt with a resistor interposed between said power supply source and said cathode heating circuit, a relay winding controlling said make and break contactor for maintaining the cathodes at an electron-emitting temperature or at a temperature below an electron-emitting condition dependent upon the effect of said resistor in said cathode emitting circuit, a keying circuit, and means in said keying circuit for energizing said relay winding in timed relation to the transmission of signals.

7. An electron tube transmission system including an electron tube circuit having a cathode and a cathode heating circuit, a circuit controller interposed in said cathode heating circuit including a resistor and a make and break contactor in shunt thereto, a keying circuit connected to said electron

tube circuit, and means controlled by said keying circuit for operating said make and break contactor for rendering said resistor effective or ineffective in said cathode heating circuit for controlling the condition of said cathode heating circuit and maintaining said cathode in an electron-emitting condition or below an electron-emitting condition.

8. An electron tube transmission system comprising a plurality of electron tubes, a cathode for each of said tubes, cathode heating circuits for said electron tubes, a power source connected with said cathode heating circuits, a resistance for limiting the energy supplied to said cathode heating circuits, a keying circuit, means controlled by said keying circuit for shunting said resistance, said means being actuated in timed relation to the operation of said keying circuit for changing the effective value of the resistance in said cathode heating circuits and maintaining said cathodes in an electron-emitting condition or at a temperature below an electron-emitting condition.

9. An electron tube transmission system comprising a plurality of electron tube circuits, a cathode for each of said tubes, a cathode supply source, cathode heating circuits for said electron tube circuits connected to said cathode supply source, resistance means interposed in said cathode heating circuits, a keying circuit, a time controlled relay governed by said keying circuit and connected to control the operation of a circuit in shunt with said resistance means in timed relation to the operation of said keying circuit for changing the effective value of the resistance in said cathode heat-circuits and maintaining said cathodes in an electron-emitting condition or at a temperature below electron emitting condition.

10. An electron tube transmission system comprising a plurality of electron tubes, a cathode for each of said tubes, cathode heating circuits for said electron tubes, a power source connected with said heating circuits, a resistance member, a relay circuit for interposing said resistance member between said power source and said cathode heating circuits or shunting said resistance member with respect thereto whereby said cathodes may be maintained in an electron-emitting condition or in a condition immediately below an electron-emitting temperature, a keying circuit and a time controlled relay controlled by said keying circuit for effecting the operation of said aforesaid relay circuit for placing said cathode heating circuit in either one of said conditions in accordance with the operation of the keying circuit.

11. An electron tube transmission system comprising a plurality of electron tubes having cathode heating circuits, a power supply circuit for energizing said cathode heating circuit, a resistance member interposed in

said power supply circuit, a relay having its contacts arranged in parallel with said resistance member, a keying circuit, a time controlled relay controlled by said keying circuit, said time controlled relay being arranged to govern the operation of said contacts for shunting said resistance member during signaling periods and maintaining a short circuit across said resistance member for a predetermined time interval after each signaling period for maintaining said cathode heating circuits in a condition of maximum energization and decreasing the energization of said cathode heating circuits after the expiration of said predetermined time interval.

12. An electron tube transmission system comprising a plurality of electron tubes, a cathode heating circuit for said electron tubes, a power source connected with said cathode heating circuit, a resistor interposed in series between said power source and said cathode heating circuit, a set of contacts connected across said resistor, a solenoid for controlling the opening and closing of the said set of contacts, a control circuit including said solenoid, a keying circuit, a time controlled relay included in said control circuit for controlling the condition of said control circuit for effecting the opening or closing of said set of contacts in timed relation to the operation of said keying circuit for changing the condition of energization of said cathode heating circuit.
